(57) **CLAIM**

The ornamental design for an adjustable support arm for lamps or the like, as shown and described.

DESCRIPTION

FIG. 1 is a top, front right side perspective view of an adjustable support arm for lamps or the like showing my new design;

FIG. 2 is a front elevational view thereof;

FIG. 3 is a rear elevational view thereof;

FIG. 4 is a left plan view thereof;

FIG. 5 is right plan view thereof;

FIG. 6 is a top plan view thereof; and,

FIG. 7 is a bottom plan view thereof.

The phantom lines shown in FIG. 1, FIG. 6, and FIG. 7 are for illustrative purposes only and form no part of the claimed design.
